14 Claims. (Cl. 315—16)

1

This invention relates to image-reproducing devices and more particularly to electrostatically focused cathode-ray tubes for use as picture-reproducing devices in television receivers and the like.

The great majority of commercially produced picture tubes for television receivers have been of the magnetically focused type, although electrostatic focusing has been employed for special applications such as cathode-ray oscilloscopes, radar, electron microscopes and the like. Magnetic focusing has been preferred for television picture tubes, in spite of its inherently higher cost, primarily for its ready adjustability, comparative freedom from lens defects such as spherical aberration, astigmatism and coma, and adaptability to mass production techniques. On the other hand, electrostatic focusing systems are attractive for their economy and simplicity, as well as for the reduction in space and weight requirements and material conservation as compared with magnetic focusing arrangements.

One of the chief deterrents to the use of electrostatic focusing systems in television picture tubes has been the commercial adoption of ion-trap arrangements for removing negative ions from the electron beam to prevent fatigue of the fluorescent screen at an excessively rapid rate. While several types of ion-trap arrangements have been devised and employed commercially, a characteristic of each is that the mixed beam of electrons and ions originating at the cathode is directed along a path displaced at least in part from the tube axis, and the electrons alone are subsequently deflected to the axis by means of one or more external magnetic fields. In order to obtain quality of focusing with an electrostatic system comparable to that achieved by magnetic arrangements, it is necessary that the electron beam be centrally projected in an axial direction through the electrostatic focusing lens; otherwise, excessive astigmatism and/or coma are encountered. These defects are accentuated with an increase in the strength of the individual lens components of the focusing system employed.

While several distinct types of electrostatic focusing systems are known, the only one which has been commercially adapted for use in modern television picture tubes is the so-called uni-potential electrostatic lens system. Fundamentally, such a lens system comprises three electrodes, the outermost two of which are operated at a common high positive potential, while the intermediate one is operated at a lower potential to provide the desired electrostatic field dis-

2

tribution comprising two convergent lens components and an intermediate divergent lens component having a net convergent effect on the electron beam. In general, the potential of the intermediate electrode has been established at from 20% to 25% of the final anode voltage. In order to employ a picture tube comprising a focusing arrangement of this type in a television receiver, it is necessary to provide special circuit components in the receiver to develop the required focusing voltage. While it is generally recognized that an electrostatic focusing system capable of providing optimum focus at focusing voltages of 500 volts or less, corresponding to the ordinary direct-voltage supply or B-supply of the receiver, would permit the elimination of the additional focusing-voltage supply circuit, no commercially acceptable television picture tube having an ion-trap type of electron gun and provided with such a focusing arrangement has been heretofore proposed. Indeed, statements may be found in the literature to the effect that an ion-trap picture tube having a focusing system which meets these specifications is beyond the realm of commercial feasibility.

It is a primary object of the present invention to provide a new and improved image-reproducing device of the cathode-ray type, having an ion-trap type of electron gun, which employs an electrostatic focusing system requiring no operating potential between that of the receiver B-supply and the final anode voltage and yet is capable of affording beam focusing comparable to that obtainable with the best magnetic focusing arrangements.

The present invention is largely predicated on the principle that undesirable lens distortion, characterized generically as multiplicity of focus and including specifically spherical aberration, astigmatism, and coma, is greatly aggravated as the strength of the individual lens components of the focusing system is increased and may be effectively minimized, even for exceedingly strong electrostatic lens components, by accurate centering of the electron beam. The problem is particularly aggravated in the case of television picture tubes employing ion traps, since the electron beam must be directed to the axis from a path displaced therefrom after separation of the ions. Consequently, the quality of focusing is largely dependent on the accuracy of alignment of the ion trap. Precise ion trap alignment by ordinary methods most widely employed in industry at the present time is extremely difficult and time consuming, even with a highly skilled

operator, and as a practical matter, is quite impossible of achievement on a large scale production basis; the best that may be achieved in commercial practice is an alignment within a range of operable conditions. Slight misalignment of the ion trap may be tolerated in a system employing a focusing voltage of 20% or more of the final anode voltage, but results in prohibitively great lens distortion with a focusing system employing stronger lens components.

In accordance with the present invention, a new and improved electrostatically focused image-reproducing device of the cathode-ray type comprises an evacuated envelope having a fluorescent-screen-bearing target portion and a neck portion which is at least partly transparent. An apertured diaphragm is positioned with its aperture symmetrical with respect to a reference axis extending longitudinally of the envelope. An electron gun is housed in the neck portion of the envelope and includes a cathode, a control electrode, and first and second accelerating electrodes for projecting an electron beam toward the fluorescent-screen-bearing target portion of the envelope, these electrodes being adapted to cooperate with a predetermined magnetic field to constitute an ion trap for intercepting negative ions originating at the cathode and for directing electrons through the diaphragm aperture along the longitudinal reference axis from a path displaced from that axis. An electrostatic focusing system comprises an additional electrode adapted to be operated at a high potential with respect to that of the cathode and a lens electrode adapted to be operated at a potential less than 5% of the first-mentioned potential, the additional electrode and the lens electrode being disposed in mutually coaxial relation with respect to the longitudinal tube axis. A fluorescent coating is included within the neck portion of the envelope and is associated with the electron gun for accurately indicating the condition of establishment of the predetermined magnetic field required for accurate axial alignment of the electron beam in the diaphragm aperture to effect optimum focusing of the electron beam on the fluorescent-screen-bearing target portion without excessive multiplicity of focus.

As employed throughout the specification and the appended claims, the terminology "a potential substantially equal to that of the cathode," as applied to the operating potential for the focusing lens electrode, is to be construed as meaning an operating potential which differs from the cathode potential by no more than the ordinary B-supply voltage employed in the associated apparatus. Conventional television receivers utilize B-supply voltages ranging from about 250 to about 500 volts and a final anode voltage for the picture tube of from 8 to 14 kilovolts. Consequently, it is apparent that a focusing voltage of 500 volts or less is generally less than 5% of the final anode voltage and may properly be considered substantially equal to the cathode potential by comparison with the final anode voltage. The term "low potential" is employed to describe a voltage not exceeding that of the receiver B-supply. A "low-potential" electrostatic focusing system is one which requires no operating voltage intermediate the B-supply voltage and the final anode voltage.

The features of the present invention which are believed to be novel are set forth with particularity in the appended claims. The inven-

tion, together with further objects and advantages thereof, may best be understood, however, by reference to the following description taken in connection with the accompanying drawings, in the several figures of which like reference numerals indicate like elements, and in which:

Figure 1 is a fragmentary side elevation, partly in cross-section and partly cut away, of an image-reproducing device constructed in accordance with the present invention;

Figure 2 is an exploded perspective view of one of the electrodes of the device of Figure 1;

Figure 3 is a schematic diagram of a television receiver embodying the image-reproducing device of Figure 1; and

Figures 4-9 are graphical representations of operating characteristics of the device of Figure 1.

The image-reproducing device of Figure 1 comprises a fluorescent screen 10 affixed to the glass target portion 11 of a cathode-ray tube envelope which also comprises a glass neck portion 12 enclosing an electron gun and an electrostatic focusing system. The electron gun comprises a cathode 13, a control electrode 14, and first and second accelerating electrodes 15 and 16 respectively. A diaphragm 17 having a central aperture 18 is disposed across the outlet end of second accelerating electrode 16, and aperture 18 is symmetrically centered with respect to the tube axis A—A perpendicular to the center of the fluorescent screen 10. Second accelerating electrode 16 is laterally offset from first accelerating electrode 15 to provide a transverse electrostatic deflection field in the region between these two electrodes, and the entire electron gun structure is tilted with respect to the tube axis A—A by an angle θ .

An electrostatic focusing system of the uni-potential lens type is disposed between the electron gun and the fluorescent screen. The focusing system comprises diaphragm 17, a lens electrode 19, and an additional electrode 20 which are all coaxially mounted with respect to the tube axis A—A. Diaphragm 17 and additional electrode 20 are maintained at a common operating potential by means of connecting strips 21, while lens electrode 19 is provided with a separate lead 22 extending through the base 23 of the tube. Additional electrode 20 is further maintained at a common potential with a conductive coating 24 of aquadag or the like on the inner wall of the tube envelope, by means of metal spacer springs 25. Conductive coating 24 extends toward the base only as far as electrode 21 to avoid undesirable spark discharge between that coating and lens electrode 19, and lead 22 may be provided with an insulating glass bead (not shown) to prevent spark discharge to electrode 16.

For convenience, electrodes 14, 15, 16, 19 and 20 may be termed "grids" and may be designated by number starting with control electrode 14 as the first grid and progressing in the direction of beam travel to additional electrode 20 which is the fifth grid. All five grids are supported in predetermined mutually spaced relation by means of a pair of glass pillars 26, of which only one is shown, in a manner which will be apparent to those skilled in the art. Separate leads for grids 1, 2 and 4 extend through the base 23 of the tube, as do the supply leads for the cathode 13 and its associated heater element (not shown). Operating voltage for the conductive coating 24, and therefore for the third and fifth

grids, may be supplied by means of a conventional contact button if the envelope is of the all-glass type, or directly to the metal cone member if the tube is of the glass-metal variety.

An external permanent magnet 21, supported in a spring clamp 28 which fits snugly around the neck of the tube and is movable both axially and rotationally, is provided to develop a magnetic field within the tube to provide separation of the negative ions from the electron beam. Moreover, a fluorescent coating 29 on the outer surface of the second accelerating electrode 16 (grid 3) is provided for facilitating alignment of ion-trap beam-bender magnet 27.

The tube is evacuated, sealed and based in accordance with well-known procedures which require no further explanation, and suitable getters 30 are supported from grid 5 to absorb residual gases after evacuation.

In operation, a mixed beam of electrons and negative ions originating at cathode 13 is projected through the aperture in first accelerating electrode 15. When the mixed beam emerges from grid 2, it encounters an electrostatic field having a transverse component due to the lateral offset of grid 3 with respect to grid 2. Consequently, electrons and ions are both deflected upwardly in the view of Figure 1. The magnetic field imposed by beam-bender magnet 27 serves to deflect the electrons in a downward direction as viewed in Figure 1 without substantially affecting the path taken by the negative ions. Thus, when beam-bender magnet 27 is accurately adjusted, the beam of electrons is projected centrally through aperture 18 of diaphragm 17 in a direction along the tube axis A—A, while the negative ions are intercepted by the metallic portions of grid 3 and diaphragm 17. The ion-trap mechanism is disclosed and claimed in the copending application of Willis E. Phillips et al., Serial No. 156,746, filed April 19, 1950, now Patent No. 2,596,508, issued May 13, 1952, for "Electron Gun for Cathode-Ray Tubes" and assigned to the present assignee.

The axially directed electron beam is subjected to the focusing action of the electrostatic fields produced by diaphragm 17, lens electrode 19 and the fifth grid 20 which together constitute a unipotential electrostatic electron lens system. The general construction and operation of lenses of this type are well understood by those skilled in the art as indicated by an article entitled "Measured properties of strong 'unipotential' electron lenses" by G. Liebmann, Proceedings of the Physical Society, section B, volume 62, part 4, pages 213-228 (April 1, 1949).

The required operating voltage for the lens electrode (grid 4) is determined by the dimensions of and the spacing between the electrodes constituting the unipotential lens. Although the relationships are not necessarily linear, the required focusing voltage varies directly with the length and inversely with the diameter of grid 4, and inversely with the separation between grid 4 and grids 3 and 5. Certain limitations on these parameters are imposed by practical considerations; if the diameter of grid 4 is made too small, excessive spherical aberration is encountered, and if the separation between grids 3 and 4 is made too great, the deflecting influence exerted by the asymmetrical electrostatic field established between lead wire 22 and grid 3 becomes objectionable.

Unipotential electrostatic lens systems have previously been employed in cathode-ray tubes.

Such lens systems have been found quite satisfactory and readily adaptable to mass production techniques when the electron gun and the focusing system are coaxial and the path of the beam is restricted to the tube axis during its entire progress from the cathode through the focusing system. However, according to present commercial practice, nearly all television picture tubes are provided with an ion-trap mechanism of one sort or another for removing negative ions from the electron beam in order to avoid deterioration of the fluorescent screen. Such types of ion-trap arrangements as are commonly employed provide ion separation by subjecting the mixed beam to opposed electrostatic and magnetic fields; both electrons and ions are transversely deflected by the electrostatic field, while the electrons only are substantially deflected in the opposite direction by the impressed magnetic field. It is apparent that the practical requirement for ion trapping results in a displacement of the electron beam from the tube axis, and it is necessary that the beam be directed to the axis before it enters the focusing system. The accuracy with which this is accomplished is of importance when magnetic focusing is employed or when a unipotential electrostatic lens system is employed with a focusing voltage source which may be varied over a relatively wide range, but slight misalignment may be compensated by varying the focusing voltage. However, the ion trap alignment becomes much more critical when satisfactory operation of the electrostatic focusing system is required within a narrow focusing voltage range between cathode potential and the B-supply voltage of the associated apparatus, owing to the increased strength of the individual lens components constituting the unipotential focusing system.

In general, if the electron beam is inaccurately centered or approaches the focusing system in an angular manner, multiplicity of focus is encountered. The most troublesome form in which this manifests itself is that of astigmatism and/or coma. In order to obtain focusing comparable with that provided by magnetic focusing systems, while operating the lens electrode at or near cathode potential, it has been found essential that the electron beam be centrally directed along the axis in its passage through the focusing system. In other words, the ion trap must be precisely adjusted for satisfactory focusing with a low-potential electrostatic lens system. Such precise alignment of the ion trap is facilitated by providing a fluorescent coating 29 on the outer wall of second accelerating electrode 16. This fluorescent coating serves as an ion-trap adjustment indicator; in practice, permanent magnet 21 is moved both axially and rotationally until the glow from fluorescent coating 29 is reduced to a minimum, thus indicating precise ion trap alignment. The fluorescent coating must of course be so situated that it is excited into fluorescence whenever the electron beam is entirely or partially intercepted by diaphragm 17, and the fluorescent glow must be visible, either directly or by reflection, through the transparent neck portion 12 of the tube envelope. Other possible locations for fluorescent coating 29 include the inner wall of neck portion 12 near the space between grids 2 and 3, the inner surface of diaphragm 17, and the surface of diaphragm 20 facing the cathode. The ion-trap indicator is described and claimed in the copending applications of Constantin S.

Szegho, Serial No. 134,725, filed December 23, 1949, now U. S. Patent No. 2,564,737, issued August 21, 1951, and of Constantin S. Szegho et al., Serial No. 162,906, filed May 19, 1950, now U. S. Patent No. 2,565,533, issued August 28, 1951, both entitled "Cathode-Ray Tube," and both assigned to the present assignee.

In order to obtain satisfactory focusing with the system shown in Figure 1, it is necessary to maintain rather stringent manufacturing tolerances with respect to the dimensions and spacings of the several electrodes constituting the focusing system. In addition, since grid 4 is to be operated at a potential substantially equal to that of the cathode, extremely high voltage gradients are produced between grid 4 and grids 3 and 5. In order to avoid undesirable corona effects and field emission, grids 3 and 5 are each provided with corona rings 31 and 32 in the form of rolled flanges of stainless steel or the like which are welded or otherwise secured to the respective electrodes, and grid 4 is constructed by rolling the two ends of a metal cylinder 33 over the edge of a large aperture in a metal disc 34. The particular construction of grid 4 is specifically claimed in the copending application of Robert W. Shawfrank, Serial No. 234,920, filed July 3, 1951, now U. S. Patent No. 2,627,049, issued January 27, 1953, for "Cathode-Ray Tube Electrodes" and assigned to the present assignee. The construction of grid 5 is illustrated in the exploded perspective view of Figure 2, and the outlet end of grid 3 is similarly constructed. Grid 5 comprises a cylindrical portion 35, an outwardly extending flange portion 36 at one end of cylindrical portion 35, and a centrally apertured diaphragm 37 across the other end of cylindrical portion 35. Corona ring 32 is supported internally of cylindrical portion 35 and is provided with a rolled rim 38 overlapping and terminally abutting flange portion 36. Thus, the electrode comprises a cylindrical portion, an apertured diaphragm across one end of the cylindrical portion, and a substantially planar flange portion extending outwardly from the cylindrical portion in a plane including the other end of the cylindrical portion; the electrode further comprises a smoothly curved corona-inhibiting portion between the cylindrical portion and the flange portion and tangential to a plane parallel to and spaced from the above-mentioned plane.

The corona rings 31 and 32 also perform an additional function in facilitating the maintenance of the required close manufacturing tolerances by mechanically reinforcing the circular flanges to which they are attached against warping or bending during the assembly of the electrode system. The electrodes are assembled by means of accurately constructed jigs and are all rigidly supported by means of a pair of opposed common glass pillars 26, the gun assembly being properly oriented in the tube neck by means of other jigs in the usual manner. It has been found that these precautions suffice to insure satisfactory operation of the completed structure, any small deviations in dimensions and spacings being readily compensated by adjustment of the ion-trap magnet 27.

As compared with the somewhat similar constructions now employed in magnetically focused television picture tubes, the electron gun of the tube of Figure 1 has been modified in two further structural respects. In the first place, the angle θ by which the entire gun is tilted with respect to the tube axis A—A is reduced from about 6 de-

grees to about $4\frac{1}{4}$ degrees, and the amount of lateral offset of grid 3 with respect to grid 2 is reduced from 1.9 mm. to 1.6 mm. In the second place, the length of the tubular portion of grid 3 is reduced from about 38 millimeters to about 30 millimeters.

These two parameters influence the performance of the electrostatic focusing system in the following manner. In order to obtain satisfactory focusing with the reduced focusing-voltage range, it is desirable to make the electron beam more nearly parallel as it enters the focusing system. This may be accomplished by locating the unipotential lens system nearer to the cathode and thereby decreasing its focal length; for this reason grid 3 is shortened. However, it is not possible to shorten grid 3 indefinitely because a certain minimum length is required to insure ion trapping at normal operating voltages. To compensate for the impaired performance of the ion trap occasioned by shortening grid 3, the amount of lateral offset between grids 2 and 3 and the angle θ by which the entire electron gun is tilted with respect to the tube axis A—A may each be increased; however, increasing the angle of gun tilt results in an increase in the angle at which the beam enters the focusing system, resulting in greater astigmatism and/or coma, so that from this point of view the angle of gun tilt should be made as small as possible consistent with the requirement for ion-trapping with a single beam-bender magnet. The condition represented by the relationships set forth in the preceding paragraph has been found to provide good focusing while retaining ion trapping at reasonable operating voltages. In this connection, it is observed that the particular type of offset ion trap employed in the tube of Figure 1 has the important advantage over other types of ion-trap gun, such as that employing coaxial electrodes with a slanted aperture between grids 2 and 3, that a greater angle of gun tilt may be employed for a given amount of lens distortion since the cathode is closer to the tube axis. Moreover, the offset type of ion trap is free of the characteristic elliptical distortion associated with the coaxial slanted-aperture type.

For best results, it has been found that the apertures in grids 1, 2, 3 and 5 should be in marginally overlapping alignment in a direction parallel to the tube axis A—A. In other words, all of these apertures should intercept an imaginary straight line parallel to reference axis A—A, and the apertures in grids 1 and 2 should intercept that line asymmetrically. Fulfillment of this condition is dependent upon the angle θ by which the entire electron gun is tilted with respect to the tube axis, and also upon the length of the electron gun from the cathode to aperture 18 in diaphragm 17. If the angle θ and/or the length of the gun is increased to such an extent that the apertures in grids 1, 2, 3 and 5 are no longer in marginally overlapping alignment in a direction parallel to the tube axis, increased multiplicity of focus is encountered, and the performance of the focusing system is inferior. On the other hand, if the angle θ is decreased so that the apertures are in complete coaxial alignment, ion trapping may no longer be conveniently accomplished with a single beam-bender magnet.

In a television receiver schematically illustrated in Figure 3, incoming composite television signals are received and separated into video-signal components and synchronizing-signal components by means of conventional receiver

circuits 40 which may include a radio-frequency amplifier, an oscillator-converter, an intermediate-frequency amplifier, a video detector, a video amplifier and a synchronizing-signal separator, as well as suitable circuits for reproducing the sound portion of the received signal. The detected composite video signal from receiver circuits 40 is applied between the control electrode 14 and the grounded cathode 13 of an image-reproducing device 41 of the type shown in Figure 1. Synchronizing-signal components of the detected composite video signal are employed to drive a synchronizing system 42 of conventional construction which supplies the line-frequency and field-frequency deflection coils 43 and 44 with suitable scanning currents to control the scans of the cathode-ray beam of device 41. A high-voltage power supply 45, which may also be of conventional construction, is employed to provide a suitable high operating voltage for the conductive coating 24 to which grids 3 and 5 are internally connected. Lens electrode 19 (grid 4) is connected to a variable tap 46 associated with a potentiometer resistor 47 connected between the receiver D. C. voltage supply source, conventionally designated B+, and ground. With the tube construction shown and described in connection with Figure 1, optimum focus of the cathode-ray beam is achieved when the minimum glow of fluorescent coating 29 indicates precise ion-trap alignment and when the lens electrode 19 is operated at a potential substantially equal to that of the cathode 13.

Several important operating characteristics of the tube illustrated in Figure 1 are shown in graphical form in Figures 4-9 inclusive. In Figure 4, the beam diameter at the center of deflection is plotted as a function of beam current, other operating parameters being maintained constant. The solid curve 50 illustrates the beam diameter versus beam current characteristic of the electrostatically focused tube shown in Figure 1, while the dotted curve 51, plotted on the same axes for purpose of comparison, represents a similar characteristic for a conventional magnetically focused cathode-ray tube. It is apparent from a consideration of the two curves that the beam diameter is less dependent on beam current in the case of the electrostatically focused tube of the present invention (in other words, the beam is maintained more nearly parallel) than with the conventional magnetically focused tube; while the spot size at the fluorescent screen is somewhat larger than that obtainable by magnetic focusing, it is also more uniform.

Figure 5 is a curve of spot size at the fluorescent screen as a function of the voltage applied to the first accelerating electrode 15 (grid 2), the remaining operating conditions being maintained constant. Grid 2 is conventionally operated at the receiver B-supply voltage, which is ordinarily between 250 and 450 volts. Within this range, the spot size decreases with increasing grid-2 voltage in a manner comparable with the performance of conventional magnetically focused tubes.

Figure 6 is a plot of the focusing voltage applied to the lens electrode 19 (grid 4) for optimum focusing conditions as a function of the operating voltage of grid 2. It is apparent from this characteristic that the B-supply voltage of the associated television receiver, within the range ordinarily employed, has no effect on the

voltage required at the lens electrode for minimum lens distortion.

Figure 7 is a graphical representation of the spot size at the fluorescent screen as a function of the voltage applied to grids 3 and 5 and conductive coating 24, the beam current being maintained constant at 200 microamperes and the focusing voltage applied to grid 4 being varied within the range of from 150 to 250 volts to maintain optimum focusing. Figure 8 is a curve illustrating the voltage required for grid 4 to maintain optimum focusing, plotted as a function of final anode voltage, the beam current also being maintained constant at 200 microamperes. From 15 a consideration of the curves of Figures 7 and 8, it is apparent that the tube of Figure 1 may be operated within a wide range of final anode voltages while still retaining satisfactory focusing with a focusing voltage between the B-supply voltage and that of the picture tube cathode.

Figure 9 is a graphical representation of the spot size at the fluorescent screen as a function of focusing voltage and beam current, the final 25 anode voltage being maintained constant at 14 kilovolts and the grid-2 voltage at 300 volts. From this family of curves, it is apparent that optimum focusing is obtained for any beam current at a focusing voltage below 300 volts, and 30 that the effect of beam current on spot size for any given focusing condition is no more pronounced than in the case of conventional magnetically focused tubes.

Merely by way of illustration and in no sense 35 by way of limitation, it may be desirable to tabulate certain critical dimensional relationships in an operative embodiment of the invention constructed in the manner shown and described in connection with Figure 1. The operating characteristics of Figures 4-9 were obtained with a 40 tube of the type shown in Figure 1 having the following dimensional relationships:

Angle θ of gun tilt	4°45'
Length of grid 3	mm 30
Lateral offset of grid 3 with respect to grid 2	inch .063
Longitudinal spacing between grid 2 and grid 3	inch .080
Diameter of aperture in grid 1	do .040
Diameter of aperture in grid 2	do .075
Diameter of aperture 18	do .100
Diameter of aperture in grid 5	do .100
Inner diameter of grid 4	do .500
Inner diameter of corona rings 31 and 32	inch .470
Axial length of grid 4	do .125
Axial spacing between grid 3 and grid 4	inch .110
Axial spacing between grid 4 and grid 5	inch .110

The dimensions of grids 3, 4 and 5 and the spacings between these electrodes are quite critical if optimum focusing conditions are to be achieved with a focusing voltage substantially equal to that of the cathode. It has been determined that uniform results may be obtained by maintaining these critical dimensional relationships within a manufacturing tolerance of plus .001 inch, minus .000 inch; while these tolerances are extremely stringent, and would be practically impossible to maintain with ordinary parts, the reinforcing effect of the corona rings on grids 3 and 5 permit ordinary manufacturing techniques to be em-

ployed while maintaining the specified close tolerances.

While the invention has been shown and described in connection with an embodiment which utilizes an ion-trap type electron gun comprising laterally offset first and second accelerating electrodes, and while the entire electron gun has been shown in a position tilted with respect to the longitudinal axis of the tube, the invention is also applicable to cathode-ray tubes employing other types of ion-trap arrangements. For example, the ion trap may be of the type comprising a pair of adjacent electrodes having complementary slanted apertures, or of the type in which the entire electron gun is curved or bent, or of any other known construction. Moreover, the electron gun may be mounted either on or parallel to the longitudinal axis of the tube, in which case a pair of beam bender magnets may be required. In any tube employing an ion-trap type electron gun, the same problems are presented when it is attempted to employ a low-potential electrostatic focusing system; in order to obtain efficient ion-trap action, the electrons must be directed to the tube axis from a path displaced from that axis, and accurate centering of the beam in the electrostatic focusing system is essential if undue multiplicity of focus is to be avoided. By employing the ion-trap indicator, accurate axial alignment of the electron beam in the focusing system is insured, and satisfactory focusing may be achieved even with an operating potential for the lens electrode which is substantially equal to that of the cathode.

While a particular embodiment of the present invention has been shown and described, it is apparent that various changes and modifications may be made, and it is therefore contemplated in the appended claims to cover all such changes and modifications as fall within the true spirit and scope of the invention.

I claim:

1. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode, and first and second accelerating electrodes adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum focusing of said beam on said target portion without excessive multiplicity of focus.

2. An electrostatically focused image-repro-

ducing device of the cathode-ray type comprising: an evacuated envelope enclosing a target portion and having a neck portion which is at least partially transparent; a diaphragm having an aperture symmetrical with respect to a reference axis perpendicular to the center of said target portion of said envelope; an electron gun housed in said neck portion of said envelope for projecting an electron beam toward said target portion of said envelope and including a cathode, a control electrode, and first and second accelerating electrodes adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum focusing of said beam on said target portion without excessive multiplicity of focus.

3. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode and first and second accelerating electrodes adapted to cooperate with a predetermined magnetic field to constitute an ion trap for intercepting negative ions originating at said cathode and for directing electrons through said aperture along said reference axis from a path displaced from said reference axis; a unipotential electrostatic focusing system comprising said diaphragm, an additional electrode adapted to be operated at a high potential with respect to that of said cathode, and a lens electrode adapted to be operated at a potential less than 5% of said first-mentioned potential; said diaphragm, said additional electrode, and said lens electrode being disposed in mutually coaxial relation with respect to said axis; and a fluorescent coating within said neck portion of said envelope and associated with said electron gun for accurately indicating the condition of establishment of said predetermined magnetic field to effect optimum focusing of said beam on said target portion without excessive multiplicity of focus.

4. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope

and including a cathode, a control electrode, and first and second accelerating electrodes individually supported with their axes inclined to said reference axis, said electrodes being adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum focusing of said beam on said target portion without excessive multiplicity of focus.

5. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode and a first accelerating electrode each supported in substantially coaxial alignment with said cathode, and a second accelerating electrode supported with its axis parallel to that of said first accelerating electrode but offset therefrom by a distance small in comparison with the diameters of said electrodes, said electrodes being adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum focusing of said beam on said target portion without excessive multiplicity of focus.

6. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode and a first accelerating electrode supported

in substantially coaxial alignment with said cathode and with their axes inclined to said reference axis, and a second accelerating electrode supported with its axis parallel to that of said first accelerating electrode but offset therefrom by a distance small in comparison with the diameters of said electrodes, said electrodes being adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum focusing of said beam on said target portion without excessive multiplicity of focus.

7. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode, and first and second accelerating electrodes adapted to cooperate with a predetermined magnetic field to constitute an ion trap for intercepting negative ions originating at said cathode and for directing electrons through said aperture along said reference axis from a path displaced from said reference axis; an electrostatic focusing system including a lens electrode and an additional electrode disposed in mutually coaxial relation with respect to said reference axis; means for operating said additional electrode at a high potential with respect to that of said cathode; means for operating said lens electrode at a potential less than 5% of said first-mentioned potential; and a fluorescent coating within said neck portion of said envelope and associated with said electron gun for accurately indicating the condition of establishment of said predetermined magnetic field to effect optimum focusing of said beam on said target portion without excessive multiplicity of focus.

8. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode, and first and second accelerating electrodes adapted to cooperate with a predetermined magnetic field to constitute an ion trap for intercepting negative ions originating at said cathode and for directing electrons through said

aperture along said reference axis from a path displaced from said reference axis; a unipotential electrostatic focusing system including said diaphragm, a lens electrode, and an additional electrode disposed in mutually coaxial relation with respect to said reference axis; means for operating said diaphragm and said additional electrode at a common high potential with respect to that of said cathode; means for operating said lens electrode at a potential less than 5% of said first potential; and a fluorescent coating within said neck portion of said envelope and associated with said electron gun for accurately indicating the condition of establishment of said predetermined magnetic field to effect optimum focusing of said beam on said target portion without excessive multiplicity of focus.

9. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode, and first and second accelerating electrodes; adjustable means for applying a magnetic field which cooperates with said electrodes to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of adjustment of said magnetic-field-producing means to effect optimum focusing of said beam on said target portion without excessive multiplicity of focus.

10. An electrostatically focused image-reproducing device of the cathode-ray type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode, a control electrode, a first accelerating electrode, and a second accelerating electrode including said diaphragm, said electrodes being adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode

and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum focusing of said beam on said target portion without excessive multiplicity of focus.

11. An electrode for a cathode-ray tube comprising: a cylindrical portion; an apertured diaphragm across one end of said cylindrical portion; a substantially planar flange portion extending outwardly from said cylindrical portion in a plane including the other end of said cylindrical portion; and a smoothly curved corona-inhibiting portion between said other end of said cylindrical portion and said flange portion and tangential to a plane parallel to and spaced from said first-mentioned plane.

12. An electrode for a cathode-ray tube comprising: a cylindrical portion; an outwardly extending flange portion at one end of said cylindrical portion; an apertured diaphragm across the other end of said cylindrical portion; and a corona ring supported internally of said cylindrical portion and having a rim overlapping and terminally abutting said flange portion for inhibiting corona discharge between said electrode and an adjacent electrode of said tube and for mechanically reinforcing said electrode against warping and bending.

13. An electrode for a cathode-ray tube comprising: a cylindrical portion; a substantially planar outwardly extending flange portion at one end of said cylindrical portion; an apertured diaphragm across the other end of said cylindrical portion; and a corona ring supported internally of said cylindrical portion and having a rolled rim overlapping and terminally abutting said flange portion for inhibiting corona discharge between said electrode and an adjacent electrode of said tube and for mechanically reinforcing said electrode against warping and bending.

14. An electrostatically focused image-reproducing device of the cathode-ray tube type comprising: an evacuated envelope enclosing a target portion and having a neck portion which is at least partially transparent; a diaphragm having an aperture symmetrical with respect to a reference axis extending longitudinally of said envelope; an electron gun housed in said neck portion of said envelope for projecting an electron beam toward said target portion of said envelope and including a cathode and a pair of electrodes adapted to cooperate with a predetermined magnetic field to constitute an ion trap for intercepting negative ions originating at said cathode and for directing electrons through said aperture along said reference axis from a path displaced from said reference axis; an electrostatic focusing system including an additional electrode adapted to be operated at a high potential with respect to that of said cathode and a lens electrode adapted to be operated at a potential less than 5% of said first-mentioned potential, said additional electrode and said lens electrode being disposed in mutually coaxial relation with respect to said reference axis; and a fluorescent coating within said neck portion of said envelope and associated with said electron gun for accurately indicating the condition of establishment of said predetermined magnetic field to effect optimum

15. An electrode for a cathode-ray tube comprising: a cylindrical portion; an outwardly extending flange portion at one end of said cylindrical portion; an apertured diaphragm across the other end of said cylindrical portion; and a corona ring supported internally of said cylindrical portion and having a rim overlapping and terminally abutting said flange portion for inhibiting corona discharge between said electrode and an adjacent electrode of said tube and for mechanically reinforcing said electrode against warping and bending.

16. An electrode for a cathode-ray tube comprising: a cylindrical portion; a substantially planar flange portion extending outwardly from said cylindrical portion in a plane including the other end of said cylindrical portion; and a smoothly curved corona-inhibiting portion between said other end of said cylindrical portion and said flange portion and tangential to a plane parallel to and spaced from said first-mentioned plane.

17. An electrode for a cathode-ray tube comprising: a cylindrical portion; an outwardly extending flange portion at one end of said cylindrical portion; an apertured diaphragm across the other end of said cylindrical portion; and a corona ring supported internally of said cylindrical portion and having a rolled rim overlapping and terminally abutting said flange portion for inhibiting corona discharge between said electrode and an adjacent electrode of said tube and for mechanically reinforcing said electrode against warping and bending.

focusing of said beam on said target portion without excessive multiplicity of focus.

CONSTANTIN S. SZEGHO.
